HAIR DIVIDER

Anthon G. Johnson, Des Moines, Iowa

Application August 4, 1937, Serial No. 157,326

10 Claims. (Cl. 132—33)

An object of my invention is to provide a hair divider of simple, durable and inexpensive construction.

A further object is to provide a hair divider which is constructed so that it will last indefinitely, the means I disclose for securing the hair gripping members thereof in position being particularly designed to make a substantial construction.

A further object is to provide a hair divider having a frame and a pair of head engaging members secured thereto with hair gripping members of rubber or the like interposed between the frame and the head engaging members so that when the frame and head engaging members are secured together, the hair gripping members are effectively and rigidly secured in their proper position.

A further object is to provide a latch for a pair of hinged frame members of a hair divider with means adjacent the latch for alining the frame members with each other when they are in latched position, thus insuring proper gripping of the hair between the hair gripping members throughout their extent.

Another object is to provide a very simple ratchet arrangement for the curling rod of the hair divider comprising a pawl integral with the frame, the frame being so constructed that the ratchet wheel on the curling rod can be automatically associated with, or manually disassociated from, the pawl without the necessity of providing a pawl which is movable relative to the frame.

Still another object is to provide ratchet and pawl mechanism for a hair divider consisting of a stationary pawl and a ratchet wheel on the curling rod coaxing therewith, the frame of the hair divider having a peculiarly shaped notch receiving the end of the curling rod adjacent the ratchet wheel which permits the desired operation of the ratchet and pawl mechanism.

Still another object is to provide a hair divider in which the hair bends as soon as it leaves the hair gripping members, thus causing the first wave in the hair to be relatively close to the head.

With these and other objects in view, my invention consists in the construction, arrangement and combination of the various parts of the device, whereby the objects contemplated are attained, as hereinafter more fully set forth, pointed out in my claims, and illustrated in the accompanying drawing, in which:

Figure 1 is a plan view of a hair divider embodying my invention, the curling rod being

omitted therefrom and the divider being shown in open position.

Figure 2 is a similar view showing the divider in closed position.

Figure 3 is a plan view of a curling rod of the usual character adapted to coact with the hair divider.

Figure 4 is an end elevation of the hair divider showing it positioned against the head of a person and showing the first step in the operation of winding the hair on the curling rod after the divider has been clamped in position adjacent the head.

Figure 4a is an enlarged sectional view on the line 4a—4a of Figure 2 showing the parts of the divider separated in solid lines and closed in dotted lines, this figure illustrating the means for retaining the two hinged portions of the divider in alinement with each other when they are in latched position without depending on the latch for this purpose.

Figure 5 is an enlarged sectional view on the line 5—5 of Figure 2 showing how the frame members and head engaging members are secured together with the hair gripping members interposed between them.

Figure 6 is a view similar to Figure 4 but on a larger scale, and showing the curling rod in its final position.

Figure 7 is a similar view illustrating the operation of the ratchet mechanism; and

Figure 8 is a sectional view on the line 8—8 of Figure 6 illustrating the latch for the hair divider.

On the accompanying drawing I have used the reference numerals 10 and 12 to indicate a pair of frame members. These are formed of flat sheet metal bent to the proper shape, the member 10 having an ear 14 to the outer end of which one end of the frame member 12 is pivoted as by a rivet or the like 16. The other end of the frame member 10 has an alining projection 18, the purpose of which will hereinafter appear. The projections 14 and 18 have laterally extending ears 20 and 22 respectively.

The base of the frame formed by the members 10 and 12 consists of a pair of head engaging members 24. These may be made of wood or other suitable material and are secured to the frame members 10 and 12 by screws or the like 26. Hair gripping members 28, which are strips of rubber or the like, are interposed between the frame members 10 and 12 and the head engaging members 24. This construction provides a very effective and rigid mounting of the hair gripping

members 28 in assembled position relative to the frame of the hair divider.

The ear 20 is provided with a notch 30, the shape of which is shown by dotted lines in Figure 7. The ear 22 is provided with a differently shaped notch 32. This notch has a portion 34 inclined away from the center of the notch and inclined away from the base of the hair divider.

A curling rod 36 is provided with spindles 38 and 40 received in the notches 30 and 32 respectively. A ratchet wheel 42 is formed on the curling rod 36 adjacent the spindle 40, and the teeth of this ratchet wheel are adapted to coact with a pawl 44 consisting of an ear bent laterally from the ear 22. The curling rod 36 is provided with the usual hinged retainer 46 to aid in starting the winding of the hair 48 on the curling rod, as shown in Figure 4, with the hair divider engaging the head 49.

20 A latch 50 is provided for the frame members 10 and 12. The latch 50 is hook-like in character and has an ear 52 hinged at 54 to an offset portion 56 of the end of the frame members 12 opposite that end which is hinged on the rivet 16. The hook portion of the latch is indicated at 58. This is adapted to be sprung over the edge 60 of the ear 22 as illustrated by dotted lines in Figure 8 for latching the parts of the hair divider in the closed position illustrated in Figures 2, 4, 30 6 and 7.

As shown in Figure 4a, prior to closing of the hair divider, the projection 18 enters the space 62 indicated between the offset portion 56 of the frame 12 and the hair gripping member 28 there adjacent. When the parts are closed, as shown by dotted lines, and as shown by full lines in Figure 6, the projection 18 is confined in the space 62 and thereby retains the frame members 10 and 12 in alinement without having to depend 40 on the latch for this purpose.

Practical operation

After the outer end of the hair 48 has been clamped under the retainer 46 of the hair curling rod, the rod is rotated in the direction of the arrow *a* for winding the hair thereon. As the hair is wound on the curling rod, the curling rod approaches the hair divider and finally assumes the position of Figure 6, with the hair loosely 50 wound on the curling rod.

Thereafter the hair can be tightened by further rotation in the direction of the arrow *a* on Figure 7, the teeth of the ratchet wheel slipping past the lower edge of the pawl 44 as the curling rod is rotated by hand. Each time a tooth is urged past the pawl, the spindle 40 is swung from the center point 64 indicated by a dot in Figure 7 in the direction of the arrow *b*. When the curling rod is released, the tension of the hair thereon tends to rotate it in the direction of the arrow *c* on Figure 6. This causes the teeth of the ratchet wheel to engage the pawl to prevent reverse rotation.

Subsequently when the hair is to be released, 65 the ratchet end of the curling rod can be pressed manually to the position of Figure 7, which releases the teeth of the ratchet wheel from the pawl and the hair, being under tension, rotates the curling rod in the direction of the arrow *c* for loosening the rod. Thereupon the rod can be removed from the hair divider and the hair unrolled therefrom.

It will be noted that the axis of the curling rod 36 is offset from the meeting edges of the 70 hair gripping members 28 so that the hair bends

sharply as it leaves these members and this enables positioning of the heat applying means on the coiled hair so that the hair is heated to a position closely adjacent the head. This causes the first wave of the hair to be relatively close to the head, thus resulting in a better appearing "permanent".

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In a hair divider, a pair of spaced frame members hinged at one end to each other, a latch for latching the other ends of said frame members together, a head engaging member for each frame member, means for securing said head engaging members to said frame members, one of said frame members having a pair of forked ears, a curling rod having spindles received in said ears and ratchet means for preventing reverse rotation of said curling rod relative to said ears, 25 said ratchet means comprising a ratchet wheel having teeth engageable in one direction on the curling rod and a pawl for coaction therewith, said pawl being stationary relative to one of said ears and the reception fork of said ear being wider than the spindle received therein to permit movement of said ratchet wheel within the fork to a position releasing the teeth thereof from said pawl.

2. In a hair divider, a pair of spaced frame members hinged at one end to each other, a latch for latching the other ends of said frame members together, a head engaging member for each frame member, means for securing said head engaging members to said frame members, 35 one of said frame members having a pair of forked ears, a curling rod having spindles received in said ears and ratchet means for preventing reverse rotation of said curling rod relative to said ears, said ratchet means comprising 45 a ratchet wheel on the curling rod and a pawl for coaction therewith, said pawl being stationary relative to one of said ears and the reception fork of said ear being wider than the spindle received therein and having an inclined edge opposite said pawl to permit movement of said 50 ratchet wheel without release from the fork to a position releasing the teeth thereof from said pawl.

3. In a hair divider, a frame having a pair of 55 forked ears, a curling rod having spindles received in said ears and ratchet means for preventing reverse rotation of said curling rod relative to said ears, said ratchet means comprising a stationary rigid pawl in the frame cooperable with a ratchet wheel on the rod.

4. In a hair divider, a frame having a pair of 65 forked ears, a curling rod having spindles received in said ears and ratchet means for preventing reverse rotation of said curling rod relative to said ears, said ratchet means comprising 70 a ratchet wheel on the curling rod and a pawl for coaction therewith, said pawl being stationary relative to one of said ears and the reception fork of said ear having a bottom wider than the spindle received therein and pitched toward the pawl to permit movement of said ratchet wheel to a position releasing the teeth thereof from said pawl.

5. In a hair divider, a frame having a pair of 75

- forked ears, a curling rod having spindles received in said ears and ratchet means for preventing reverse rotation of said curling rod relative to said ears, said ratchet means comprising a ratchet wheel on the curling rod and a pawl for coaction therewith, said pawl being stationary relative to one of said ears and the reception fork of said ear being wider at the bottom than the spindle received therein and having an inclined edge opposite said pawl to permit movement of said ratchet wheel laterally to a position releasing the teeth thereof from said pawl.
6. In a hair divider, a frame, a curling rod, said frame having notched ends to receive the ends of said curling rod, a pawl extending from said frame, said curling rod having a ratchet wheel for coaction therewith, the notch adjacent said pawl being wider than the end of the curling rod received therein to permit lateral movement of said curling rod to a position releasing the teeth of said ratchet wheel from said pawl.
7. In a hair divider, a frame, a curling rod, said frame having notched ends to receive the ends of said curling rod, a pawl extending from said frame, said curling rod having a ratchet wheel for coaction therewith, the notch adjacent said pawl being wider than the end of the curling rod received therein to permit lateral movement of said curling rod to a position releasing the teeth of said ratchet wheel from said pawl, said last mentioned notch having the edge thereof opposite said pawl inclined away from the center of the notch and away from the base of the frame.
8. In a hair divider a hair gripping member having a pair of separable elements, a pair of spaced frame members hinged at one end to each other, a latch for clamping the other ends together, and a pair of head engaging members secured respectively one to each of said frame members and said separable elements, said head engaging members being positioned in spaced relation so that hair strands are gripped at a predetermined distance from the scalp.
9. In a hair divider, a frame having a pair of spaced frame elements hinged at one end to each other, a latch for latching the other ends together, said frame having a pair of forked ears and curling rod receivable in said forks having a ratchet means at one end for preventing reverse rotation thereof, one of said ears being provided with a pawl for engagement with the ratchet and having its forked portion wider than the diameter of the rod end with the bottom thereof positioned nearer the scalp at the side adjacent the pawl so that the center line of the rod when received therein is shifted nearer the scalp than the pawl and ratchet engagement in order that a pull exerted by the strands of hair will lock the curling rod in place.
10. In a hair divider a hair gripping member having a pair of separable elements, a pair of spaced frame members hinged at one end to each other, a latch for clamping the other ends together, and a pair of head engaging members secured respectively one to each of said frame members and said separable elements, said head engaging members being positioned in spaced relation so that hair strands are gripped at a predetermined distance from the scalp, a curling rod for curling the hair, notched ends on the frame to receive the ends of the curling rod, a pawl extending from said frame and a ratchet wheel on the curling rod for coaction therewith, the notch adjacent said pawl being wider at the bottom than the diameter of the end of the curling rod received therein to permit lateral movement of said curling rod to a position releasing the teeth of said ratchet wheel from said pawl.

ANTHON G. JOHNSON. 40
